UNITED STATES PATENT OFFICE.

IRA J. OWEN, OF GRAND RAPIDS, MICHIGAN, ASSIGNOR TO BISSELL CARPET SWEEPER COMPANY, OF GRAND RAPIDS, MICHIGAN.

FRAMEWORK FOR VACUUM-CLEANER CARPET-SWEEPERS.

1,371,432.

Specification of Letters Patent.

Patented Mar. 15, 1921.

Application filed April 26, 1920. Serial No. 376,676.

To all whom it may concern:

Be it known that I, IRA J. OWEN, a citizen of the United States, residing at Grand Rapids, Kent county, Michigan, have invented certain new and useful Improvements in Framework for Vacuum-Cleaner Carpet-Sweepers, of which the following is a specification.

This invention relates to improvements in general features of the framework of vacuum cleaner carpet sweepers.

The object of the invention is to provide a convenient and effective means and construction lending itself to ready standardization and assembly of the parts.

Objects which relate to details will definitely appear from the detailed description to follow.

I accomplish the objects of my invention by the devices and means described in the following specification. The invention is clearly defined and pointed out in the claims.

A structure which is a preferred embodiment of my invention is fully illustrated in the accompanying drawing, forming a part of this specification, in which:

Figure I is a side elevation view of a combination vacuum cleaner and carpet sweeper embodying the features of my invention, with the parts completely assembled.

Fig. II is a detail side elevation view with the interior sweeper and bellows supporting frame dropped out of the case and left in juxtaposition thereto to show the method of assembling, portions of the outer case being broken away to show details.

Fig. III is a detail transverse sectional view taken on line 3—3 of Fig. I, looking in the direction of the little arrows at the ends of the section line.

In the drawings similar numerals of reference refer to similar parts throughout the several views.

Considering the numbered parts of the drawing, 1 is the outer shell or casing which is here made in the form of an open bottom box of suitable form, notched at the front to accommodate the nozzle block 3. 2 is the inner casing or box which carries the carpet sweeper 4 below and contains the vacuum chamber 5 within which is disposed the dust bag 5' above the carpet sweeper, and on its upper wall 6 carries the bellows 6', so that within this casing, in a suitable unitary

structure which can be very readily removed by withdrawing the retaining screws 7, the entire working parts of the carpet sweeper and bellows can be withdrawn. This permits standardization of the construction and the use of outer cases of different finishes for different grades of machines.

The carpet sweeper wheels 4' project at the sides of the machine and their axles are below the bottom edge of the outer case 1 and the tops of the wheels extend above the bottom at each side. The bellows 6' are connected by suitable detachable pitmen 6'' to the crank shaft 10 at the rear. The propelling wheels 8 for the vacuum cleaner carry this crank shaft. These are made conveniently detachable by hanger blocks 9 which are supported in place on the outer case by screws 11 (Fig. I), making the assembling of parts a very simple operation.

By providing the outer case with the vacuum cleaner floor wheels thus disposed in the rear thereof and providing the carpet sweeper and bellows structure in a unitary structure on an internal box which can be readily removed bodily from the machine, assembling and repair are greatly facilitated. The entire operating parts of the bellows and carpet sweeper can be made up in plain lumber, yet the outer case can be given a handsome finish to drop over the same, and by locating the vacuum cleaner driving means in the space at the rear of the machine and providing these driving means with hangers that are readily detachable, it will be seen that a standardization of structure is possible in all particulars, so that to produce the different grades of vacuum cleaners and sweepers it is only necessary to select and assemble the different and appropriate parts.

Having thus described my invention what I claim as new and desire to secure by Letters Patent is:

1. In a vacuum cleaner and carpet sweeper, the combination of an outer casing open at the bottom, with driving floor wheels and crank shaft disposed in the rear for driving the vacuum cleaner, an internal, unitary, removable, box-like structure at the front thereof, the upper wall of which constitutes a bellows board, a vacuum chamber beneath the said board, a carpet sweeper beneath the vacuum chamber supported between the side walls of said box, and a suit-

able nozzle block at the front of said vacuum chamber conformed and fitted to the outer casing, all coacting substantially as described for the purpose specified.

- 5 2. In a vacuum cleaner and carpet sweeper, the combination of an outer casing open at the bottom, with driving floor wheels suitably secured thereto, a removable, unitary box-like structure at the front thereof
10 comprising a bellows and vacuum chamber and carpet sweeper structure, and a suitable

nozzle box at the front of said unitary structure and conformed and fitted to the outer casing, as specified.

In witness whereof, I have hereunto set 15 my hand and seal in the presence of two witnesses.

IRA J. OWEN. [L.S.]
